Attorneys

UNITED STATES PATENT OFFICE.

JOHN GIESY, OF TACOMA, WASHINGTON.

FEEDING DEVICE.

1,361,045.

Specification of Letters Patent. Patented Dec. 7, 1920.

Application filed June 27, 1919. Serial No. 307,214.

To all whom it may concern:

Be it known that I, JOHN GIESY, a citizen of the United States, residing at Tacoma, in the county of Pierce and State of Washington, have invented certain new and useful Improvements in Feeding Devices; and I do hereby declare the following to be a full, clear, and exact description of the invention, such as will enable others skilled in the art to which it appertains to make and use the same.

This invention relates to chick feeding devices, and especially to a device for automatically supplying a quantity of fluid substance or material as it is consumed by chickens or other stock which may be feeding from the device.

It is an object of the present invention to provide a simple, practicable, substantial, durable, readily adjustable and inexpensive device from which may be exhausted fluid substances such as, for instance, water, milk, and clabber.

Another object of the invention is to provide an article, the several parts of which are easily renewable and interchangeable, and which can be readily cleansed, so that the device can be kept in a thoroughly sanitary condition.

With the above and other objects in view, as will be readily manifest to those versed in the art, the invention consists of the construction, the combination, and in details and arrangement of the parts as more particularly described in the following specification relative to the embodiment of the invention illustrated in the accompanying drawings, wherein:

Figure 1 is a perspective view of the device showing a jar in adjusted position, the guard ring being in position to be lowered onto the top of the container.

Fig. 2 is a fragmentary view of the rear end of the spring clamp.

Fig. 3 is a vertical central section through the completely assembled feeder.

Fig. 4 is a plan view of the container with the guard ring removed and the jar in cross section.

Among the purposes of this invention one is to provide a liquid feeding device which will maintain constantly a suitable supply of liquid feed, and further, I provide a device with which an ordinary Mason jar or similarly sized vessel can be used, so that I am enabled to manufacture and sell the holders

and the purchasers can utilize jars that they already have in their possession, although, of course, the jars, or a suitable jar, can be sold with the container.

Therefore I have shown an ordinary form of Mason jar J as inverted in Figs. 1 and 3 and clamped by the resilient action of a pair of semi-circular or arcuate spring arms 2-2 which extend in crossed relation from a back bar or connector 3, clearly shown in Figs. 2 and 4.

The connector is provided at its ends with a pair of U-shaped bows 4-4, the parallel arms of each of which are spaced sufficiently to encompass the rim of a suitable vessel or container in the form of a metallic cylinder 5, the cross bar of the coupler 3 being curved to conform to the curve of the cylinder, while the ends 6-6 of the arms 2-2 are designed to extend for a suitable distance around the inside surface of the container 5 when the coupler is mounted on the edge thereof, as clearly shown in Figs. 1 and 3.

The swinging or other ends of the clamping arms 2-2 are shown as provided with suitable rests or bowed portions 7-7 designed to overlap the rim of the container 5, so that when the jar J is introduced between the opposed jaws or arms 2-2 and the latter are released from the dotted position in Fig. 4 the jar is embraced in a substantial manner and supported by the holder or clamping device, which latter is supported at two diametrically opposite portions of the rim of the container 5.

In this manner the jar can be held in a suitable position above the bottom of the container 5 so that the liquid from the inverted jar J will, under gravitation, automatically replace the quantity contained in the bottom of the vessel 5 as it is withdrawn by chicks or other stock having access to the interior of the container 5 through means of suitable apertures or openings 10, a number of which are formed at a suitable height and at suitable locations around the wall of the cylinder or container 5.

To prevent access to the interior of the container other than through the apertures or openings 10 I prefer to provide a guard ring or cover-like annulus 11 having a central aperture 12 of a diameter sufficient to receive the jar J and having at its perimeter a downturned flange 13 covering the rim of the container 5.

In the use of the device, the parts of the

feeder being properly assembled, the jar J can be filled and the feeder placed over the top opening or mouth of the jar when the latter is in an upright position, and then, by 5 quickly inverting the jar with the container to the position shown in Fig. 3, the liquid will gravitate downwardly and rise in the container to a height determined by the elevation of the mouth of the jar J. The guard 10 ring 11 can then be set in place by being passed down over the upwardly extending end of the jar J.

Having thus described my invention, what I claim is:

- 15 1. In a feeder having a receptacle with openings, a clamping device of spring wire comprising two crossed arcuate arms, a back bar connecting said arms, said back bar having an inverted U-shaped bar at each side adapted to engage the side of the receptacle.
- 20 2. A chick feeder having a receptacle with

openings in its side wall, a spring clamp consisting of a piece of wire having a connecting part to interlock with the rim of the receptacle, and a pair of crossed arcuate arms with saddle ends to rest upon the rim of the receptacle, and a jar adjustably held by the frictional engagement of said arms at any desired elevation above the bottom of the receptacle. 25

3. A chick feeder having a receptacle with openings in its side wall; a clamp consisting of a piece of wire having a connecting part to interlock with the rim of the receptacle and having a pair of bowed arms with saddle 35 ends to rest upon the rim of the receptacle, and a jar adjustably held by the arms at a suitable elevation above the bottom of the receptacle.

In testimony whereof I affix my signature. 40

JOHN GIESY.
